OF D 12,613

DESIGN FOR A STOVE.

Design No. 12,613, dated December 20, 1881.

Cut 278.

UNITED STATES PATENT OFFICE.

H. CLAY BASCOM, OF TROY, NEW YORK, ASSIGNOR TO N. S. VEDDER PAT-
TERN WORKS, BASCOM, GALBRAITH & CO., OF SAME PLACE.

DESIGN FOR A STOVE.

SPECIFICATION forming part of Design No. 12,613, dated December 20, 1881.

Application filed November 16, 1881. Term of patent 7 years.

To all whom it may concern:

Be it known that I, H. CLAY BASCOM, a citizen of the United States, residing in the city of Troy, in the county of Rensselaer and State of New York, have invented and produced a new and original ornamental Design for a Stove, of which the following is a specification, reference being had to the accompanying cut, print, or engraving of a stove having my said new design.

One feature of my invention is the design for the compound top ornament, A, consisting of the flask-shaped middle part, b, the saucer-shaped part c, having a serrated rim and mounted on the part b, the ornamental cross d, rising out of the part c, and two wing-plates, e, extending from opposite sides of the part b, and pointed at their lower ends, conformed at their tops to the part c, and having incut face ornaments and ornamenteally-curved outer and inner edges, and all the parts being shaped and arranged together so as to appear substantially as represented in the aforesaid cut.

Another part of my invention is the design for the dome-plate B, the same being of an oblong convexly-curved form, with a central concavely-curved raised part, g, and having upon each convexly-curved end part and side part the compound ornament composed of the pair of connected scroll ornaments h h' and intermediate leaf ornaments, i i', while on the spaces between said compound ornaments are the oblong curve-sided triangles k, inclosing ribbed grounds k', all shaped and disposed together as shown in the accompanying cut.

Another part is the design for the front of the upper section, consisting of the swelled quadrilateral panel C, having therein the name-plate m, formed with ornamental ends and matted ground m', and extending in reversely-curved form diagonally across the plain surface n n', having therein the compound corner ornaments composed, essentially, of the radial net-work n' n² in the angles, curved scallop-edging o, and scroll ornaments o' o', with intermediate Gothic points, p p, and top and bottom ornaments, p' p², all shaped and arranged together as shown in the accompanying engraving.

Another feature is the design for the front

door, D, of the lower section, consisting of the upper panel, E, having the series of border-moldings a along the top and sides of the plane surface f, in which are the three rectangular mica-light openings l, with upwardly-pointing top angles, l', and the intermediate rib-surfaced oblong pointed ornamentations, q, in combination with the lower projecting vertically-convex oblong panel, F, having therein the series of four rectangular draft-apertures r, with upwardly-pointing top angles, r', and the surrounding and intervening incut ornamentations s, all shaped and arranged together substantially as shown in the aforesaid print.

Another part is the design for the end door, G, consisting of the lower projecting tablet portion, H, having the horizontally-convex upright surface, in combination with the upright horizontally-convex upper portion, I, having thereon the pairs of compound scroll and leaf ornamentations t t' t² t³ and the lower check-work corner ornaments, u, all shaped and arranged together substantially as shown in the aforesaid cut.

Another part is the design for the legs, consisting of the swelled upper portion, J, having the scalloped and reversely-curved borders v v, the leaf w on the heart-shaped central part, w', bordered by the incut ornaments x, extending on to the contracted lower part, x', and flanked by the grooved upper corner ornaments, y y, having the inner concave edges, z, and outer wavy edges, z', and all shaped and combined as shown in the accompanying engraving.

What I claim as my invention is—

1. The design for the top ornament, A, consisting of the parts b, c, d, and e e, all shaped and combined as set forth.

2. The design for the dome-plate B in the form shown, and having the ornaments h h', i i', and k k', all shaped and arranged together as set forth.

3. The design for the front of the upper section, consisting of the parts C m m' n n' n² o o' p p' p², all shaped and combined as set forth.

4. The design for the front door, D, of the lower section, consisting of the parts E a f l l' q and F r r' s, all shaped and combined as set forth.

5. The design for the end door, G, consisting of the parts H I t t' t² t³ u, all shaped and arranged as shown and described.

6. The design for the legs, consisting of the 5 parts J v v w w' x x' y y z z', all shaped and combined as set forth.

In testimony whereof I hereunto set my

hand, in the presence of two subscribing witnesses, this 14th day of November, 1881.

H. CLAY BASCOM.

Witnesses:

AUSTIN F. PARK,
JAMES T. GOODFELLOW.
